HYDRAULIC CONTROL FOR PUMPS AND THE
LIKERoss B. Treer, Lakewood, Ohio, assignor of one-
half to Edwin J. Hull, Cleveland, Ohio

Application March 19, 1940, Serial No. 324,814

5 Claims. (Cl. 103—173)

My invention pertains to adjustable multiple impeller pumps and more particularly to a quick adjustable pump having a hydraulically operated adjusting mechanism, and the present invention is an improvement on the pump disclosed in my copending patent application, Serial Number 296,896, filed 10/28/39, and the copending application of Edwin J. Hull, Serial Number 309,066, filed December 13, 1939.

It is an object of my invention to provide a multiple impeller pump, such as that disclosed in the above mentioned patent applications, having combined therein hydraulic actuator mechanism and control means for applying the fluid pressure of the pumped fluid for conveniently and quickly adjusting the pumping capacity of each pumping impeller of the pump.

It is also an object of my invention to provide such a pump having a plurality of pump plungers and guide passages, each plunger sliding into one end of an individual guide passage, a pair of ports opening into each guide passage at axially spaced points, a check valve plunger slideable into the opposite end of each guide passage and approaching the inner end of each pump plunger in the inter-port portion of the passage to positively prevent reverse flow of fluid from the outlet port to the inlet port and to determine the quantity of fluid to be trapped in the interport passage by each stroke of each pump plunger, biasing means urging each valve plunger to move into said passage past the outlet port to positively cut off reverse flow of fluid therein from the outlet port to the inlet port, stop means for limiting the movement of each valve plunger into the passage, means for adjustably supporting the stop means for movement to various positions to adjustably limit the inward movement of said valve plunger by the biasing means to predetermine the quantity of liquid trapped in the interport portion of the passage to be displaced by each inward movement of the pump plunger, hydraulic actuator means for moving said stop means, conduit means, and control valve means associated with said conduit means and arranged for selectively increasing, holding constant or decreasing the pump capacity by selectively connecting the hydraulic actuator either to receive high pressure pumped fluid to move the stop means to oppose the movement of the valve plunger by the biasing means, or to a neutral position to seal in received fluid, or to a position to open a discharge connection for discharging fluid from the hydraulic actuator in response to pressure applied thereon by the valve plunger biasing means.

Further objects and advantages are within the scope of my invention, such as relate to the arrangement and function of the related elements of the structure, to various details of construction and to combination of parts, elements per se, and to economies of manufacture and to numerous other features as will be apparent from a consideration of the specification in conjunction with the drawings disclosing a specific form of my invention, similar reference characters being applied to similar parts throughout, and, in which:

Fig. 1 is a longitudinal sectional view through the quick adjustable multiple impeller pump and with the manually actuatable valve set for holding the adjustment constant;

Fig. 2 is a similar view of a portion thereof showing the manual valve set for injecting high pressure pumped fluid into the hydraulic actuator for increasing the pumping capacity, the conduit passages being connected to but one pumping unit instead of to a plurality of such units.

Fig. 3 is a similar view of a portion thereof showing the manual valve set for releasing fluid from the hydraulic actuator to decrease the pumping capacity, the conduit passages being connected to but one pumping unit instead of to a plurality of such units.

Referring more particularly to Fig. 1 of the drawings, my quick adjustable pump comprises a pump body 1 having an inlet port 3 and an outlet port 5 opening into the body and intercepting a cylindrical guide passage or bore 7 at axially spaced points thereof. The guide passage 7 is drilled through the pump body 1 and the opposite ends of the passage open from opposite sides of the body. The portion 9 of the guide passage 7 to the right of the inlet port 3 serves as a guide passage for slidably receiving a pump plunger 11 and the left hand portion 13 to the left of the outlet port 5 serves as a guide passage for a valve plunger 15 and the interport passage 7 at times receives the inner ends of both plungers in a manner to be subsequently described. The intermediate portion 7 of the guide passage may for convenience be termed the inter-port passage or it may be regarded as a valve inlet passage since all the fluid approaches the valve plunger 15 through this passage.

As shown, another pair of ports 3 and 5 enter the opposite side of the pump body 1 in spaced relation and similarly intercept a cylindrical guide passage 7 at axial spaced points along the passage cooperating with a pump plunger 11 and a check valve plunger 15 in a similar manner. It

is to be understood that any desired number of the guide passages 7 may be provided in the body 1, each having similarly associated plungers and ports, and being for compactness and convenience of control preferably disposed in a circular or cylindrical arrangement about the central axis of the valve body 1. As will be understood, the inlet ports 3 may all open into the body separately and each outlet port 5 may open therefrom separately so that each pump operates as an individual pump independently from the others except for a common drive and a common adjustment, to be subsequently described. The outer ends of the ports 3 and 5 may be provided with any suitable pipe fitting arrangement for convenient connection with pipe lines.

A drive shaft 17 has one end journaled in a bearing 19, centrally disposed in the end of the pump body, and which may be of a friction reducing type having steel ball bearings 21. The other end of the drive shaft is journaled in a friction reducing bearing 23 centrally disposed in an end cover plate 25 from whence the drive shaft is extended for connection with any suitable external source of power (not shown). The journaled portions of the drive shaft are in axial alignment and are connected through an intermediate portion 27 which is relatively inclined for tilting a wobble collar 29 journaled thereon, as shown, and more fully described in my previously mentioned patent application. Similarly arms 31 extend laterally with projecting ball connectors 33 extending into U-shaped sockets 35 on the ends of the pump plungers 11 which are thereby reciprocated in the guide passages 9 as the drive shaft 17 rotates. From the adjacent side of the pump body 1 a shell 37 extends, enclosing a chamber 38 around the driving mechanism and has a thick internal flange 39 around the outer end to which the cover plate 25 is attached by bolts 41 passing therethrough. Any suitable lubricant may be provided in the enclosing chamber for lubricating the driving mechanism of the pump.

From the opposite side of the pump body, a shell 43 extends defining a valve chamber 44 which encloses the valves and the valve adjusting mechanism. A cover 45 is snugly secured to the outer edges of the shell 43 as by bolts 47 passing therethrough. The cover 45 is provided with an aperture 49 in alignment with each valve plunger 15 and suitably threaded for receiving a threaded plug 51. In the outside of each plug 51 is a suitable aperture for receiving a wrench for screwing the plug into or out of the cover. A spring receiving recess 55 is provided in the inner end of each plug 51 for receiving the outer end of a compression valve spring 57, the inner end of which presses against a lateral flange 59 on the valve plunger 15 which is thereby continuously biased to enter the valve guide passage 13. A guide pin 60 extends from the valve plunger 15 concentrically into the spring 57.

Stop means is provided for limiting the inward movement of the spring biased valve plunger 15 for which purpose I provide an adjustable stop member or collar 61. The stop collar 61 is of a generally circular or annular conformation having recesses 63 through which the valve plungers 15 slide freely until the inward movement of each plunger is limited by the engagement of each lateral flange 59 against the stop collar 61. The central portion of the stop-collar is axially elongated to provide a cylindrical cavity 65 centrally disposed therein and slidable upon a stationary

5 piston member 67 which projects thereinto from the central portion of the valve body 1. The cylinder 65 of the stop collar 61 slides over the stationary piston 67 in snug fluid retaining relation and the latter has circumferential packing receiving grooves 69 for receiving any suitable packing material 71 therein to provide a snug fluid retaining seal.

10 Passing centrally through the stationary piston 67 is a central cylindrical bore 73 which extends into the center of the pump body 1 and connects at the inner end through a passage 75 to one of the inlet ports 3. Opening from the outlet port 5 is a passage 77 which intercepts 15 the central bore 73 through an axially elongated slot 79 in the side wall thereof. Opening centrally through the stop collar 61 and cover 45 are cylindrical bores 81 and 83 in alignment with the central bore 73 in the body and of a similar diameter. From the cylinder 65 in the stop collar 61 a passage 85 extends and opens through the side wall of the central bore 81 passing therethrough by way of two diametrically opposed ports 86 or a single semi-circular groove port.

20 A manual valve plunger 87 slides in snug fluid retaining relation through the central bores 83, 81 and into the central bore 73 in the valve body 1. From the inner end of manual valve plunger 87 two passages 89 and 91 are drilled axially 25 therein, the latter being closed by a plug 92 at its inner end. The axial passages 89 and 91 open outwardly through ports 93 and 95 in the outer side wall of the portion of the manual valve plunger 87 which slides through the bore 81 in the stop collar 61 for conductive connection with the port 86 therein. The ports 93 and 95 open 30 from the outer wall of the manual valve plunger 87 at axially spaced points therealong such that either passage 89 or 91 may be conductively connected with port 86 selectively or when the plunger rests at an intermediate position, the port 86 from the cylinder 65 is closed to seal fluid previously received therein. From adjacent the other end of the axial passage 91 a port 97 opens laterally for continuous connection with the elongated slot port 79 in all positions of the plunger for continuously applying the high pressure pumped fluid therein from the outlet port 5.

35 For convenience in adjusting the position of the manual control valve plunger 87 I provide a hand lever 99 the lower end of which is pivotally connected by a pivot pin 101 to one end of a link 103 extending pivotally from a pivot pin 102 in a bracket member 104 on the cover 45. 40 The outer end of the manual control valve plunger 87 is connected to an intermediate portion of the hand lever 99 by a pivot pin 105. The operator grasps the upper end of the hand lever and because of the leverage obtained easily moves the manual control valve plunger 87 in or out of the pump to quickly and conveniently adjust the per stroke pumping.

45 In operation the drive shaft 17 is rotated by any external source of power causing the pump plungers 11 to reciprocate in the guide passages 9 in a manner more fully described in my co-pending patent application previously mentioned. As a pump plunger moves to the right out of the inter-port passage, fluid rushes in from inlet port 3 to fill the space evacuated by the plunger. Moving to the left, the inner end of the pump plunger starts to enter the adjacent end of the inter-port passage 7 trapping therein a quantity 50 of fluid which is then pushed forcefully along, moving the check valve plunger to the left, open-

ing to the outlet port 8 and discharging therefrom. As the pump plunger 11 moves to the right, the check valve plunger follows and, entering the other end of the inter-port passage 1, positively restricts the reverse flow of fluid from the outlet port 5 through passage 7 toward the inlet port 3. The distance that the inner end of the valve plunger enters into the inter-port passage 1 determines the quantity of liquid that will be trapped therein by the next inward movement of the pump plunger and this is determined by the position of the stop collar 61 which by engagement with flange 59 on the valve plunger limits its extreme inward movement.

To conveniently and quickly adjust the stroke 15 by stroke pumping capacity of the pump plungers to suit all conditions of demand and of the density and viscosity of different liquids to be dispensed, it is only necessary for the attendant to shift the hand lever 99.

To increase the capacity of the pump, the lever 99 is moved to the left to draw the manual control valve plunger 87 to the left until port 85 therein is conductively connected with the port 86 in the stop collar 61, as shown in Fig. 2, when high pressure pumped fluid flows from outlet passage 5 by way of passage 11, slot port 19, plunger port 91, plunger passage 81, plunger port 85, stationary port 86, and thence by way of passage 85 into the cylinder 65. As the high 30 pressure pumped fluid enters the cylinder 65 in the stop collar 61, the entire stop collar is caused to slide back on the stationary piston support member 67 thereby engaging all the lateral flanges 59 on all the sliding valve plungers 15 at 35 an earlier point of the inward movement thereof. The inner ends of the valve plungers must still enter the adjacent ends of the interport passages 1 to serve their functions as check valves, but because of not entering so far into the interport passages a larger quantity of liquid is received therein to be advanced by the next inward movement of the respective pump plungers.

When the pump capacity has been sufficiently increased, the lever 99 is actuated to move the control valve plunger 87 to the neutral position when the plunger ports 83 and 95 are disposed as shown in Fig. 3, on opposite sides of the stationary port, 86, which is thus closed to seal in the cylinder 65 the liquid received therein. Or as the stop collar 61 moves to the left, ports 83 and 95 are automatically disposed on opposite sides of port 86. In the neutral position of the lever 99, the adjustment of the pump is held constant.

When it is desired to adjust the pump to decrease the pumping capacity of each pump plunger, the lever 99 is moved to the right moving the control valve plunger 87 to the right until the plunger port 83 conductively connects with the stationary port 86, as shown in Fig. 3. In this position the fluid previously injected into the cylinder 65 escapes by way of passage 85, ports 86 and 93, axial passage 89 in the plunger 87, into the central bore 73 at the inner end of the control plunger 87, thence by way of passage 15 in the pump body to the low pressure inlet port 3. The tension of all the compression valve springs 57 pushes the stop collar member 61 to the right expelling fluid from the cylinder 65 until the hand lever 99 is again moved to a neutral position.

It is apparent that within the scope of the invention, modifications and different arrangements may be made other than therein disclosed,

and the present disclosure is illustrative merely, the invention comprehending all variations thereof.

I claim:

1. A compact adjustable capacity multiple impeller pump comprising, a pump block, a plurality of guide passages in said pump block and opening therefrom at the opposite ends, said guide passages being disposed substantially parallel to each other in a substantially cylindrical arrangement in said pump block, an inlet port and an outlet port opening into each guide passage at axially spaced points therein, a pump plunger slideable back and forth in fluid displacing relation in the end of each guide passage adjacent the inlet port for opening and closing the inlet port and for moving entrapped fluid through the interport passage toward the outlet port, a drive shaft journalled substantially centrally with reference to the cylindrical arrangement of the guide passages in the pump block, power transmission means operatively connecting between said drive shaft and the pump plungers for reciprocating the plungers as the shaft rotates, a check valve plunger slidably disposed in the other end of each guide passage adjacent the outlet port, means for continually biasing each valve plunger into the guide passage to move in past the outlet port and into the interport passage, a stop member for limiting the movement of all of said valve plungers into the passages, means for adjustably supporting said stop member for movement to simultaneously adjust the innermost position of all said valve plungers to predetermine the quantity of entrapped liquid in the interport portion of each passage to be displaced by each inward movement of each pump plunger, a hydraulic actuator for moving said stop member, conduit means, and control valve means conductively connected with said hydraulic actuator and said conduit means and arranged for selectively operating said hydraulic actuator to move the stop member in either direction, or to hold stationary.

2. A compact adjustable capacity multiple impeller pump comprising, a pump block, a plurality of guide passages in said pump block and opening therefrom at the opposite ends, said guide passages being disposed substantially parallel to each other in a substantially cylindrical arrangement in said pump block, an inlet port and an outlet port opening into each guide passage at axially spaced points therein, a pump plunger slideable back and forth in fluid displacing relation in the end of each guide passage adjacent the inlet port for opening and closing the inlet port and for moving entrapped fluid through the interport passage toward the outlet port, a check valve plunger slidably disposed in the other end of each guide passage adjacent the outlet port for opening or closing the outlet port, a valve spring for continually biasing each valve plunger into the guide passage to move in past the outlet port and into the inter-port passage, a stop collar having apertures through which the valve plungers slide, engageable means on each valve plunger for engaging the stop collar for limiting the movement of each valve plunger into each passage, means for movably supporting said stop collar for movement to various positions relative to the pump block to predetermine the quantity of entrapped liquid in the interport portion of each passage to be displaced by each inward movement of each pump plunger by adjusting the extent of the in-

sertion of the inner end of each valve piston into the inter-port passage, a hydraulic actuator for shifting said stop collar, conduit means, and manually movable control valve means conductively connected with said hydraulic actuator and said conduit means and arranged for selectively operating said hydraulic actuator to move the stop collar in either direction.

3. The combination with a multiple impeller pump comprising, a pump block having a plurality of guide passages, an inlet port and an outlet port opening at axially spaced points into an intermediate portion of each passage, a pump plunger slidable back and forth into the end of each passage adjacent the inlet connection, a check valve plunger slidable in the other end of each passage for opening and closing the outlet connection and for predetermining the quantity of fluid to be trapped in the intermediate portion of each passage between the inlet and outlet port connections, of means for controlling the pumping capacity of all of the pumps simultaneously comprising an engageable means on each valve plunger, an apertured stop collar through which the valve plungers pass for engaging the engageable means for limiting the inward movement of each spring pressed valve plunger, a piston projection extending centrally from the pump body toward the stop collar, a central cylinder recess in the stop collar for receiving said piston projection in slidable fluid retaining relation therein for supporting said stop collar for movement to various positions relative to the pump block to predetermine the inner extreme position of the valve plungers for adjusting the quantity of entrapped liquid in the interport portion of each passage to be displaced by each inward movement of each pump plunger, said cylinder recess and piston projection forming a hydraulic actuator for moving said stop collar, conduit means, and control valve means conductively connected with said cylinder recess and said conduit means and arranged for selectively connecting the cylinder recess with the pump inlet or outlet or for disconnecting it from either.

4. A compact adjustable multiple impeller pump comprising the combination set forth in claim number 3 in which the control valve means includes a manually actuatable control valve plunger sliding through central apertures in said stop collar and the piston projection, and conduit means controlled thereby including passages ex-

5 tending along in the plunger and opening laterally from the sides of the plunger for selectively connecting conductively with and between the cylinder recess and the inlet and outlet passages in the pump body.

5. A compact adjustable capacity multiple impeller pump comprising, a pump block, a plurality of guide passages in said pump block and opening therefrom at the opposite ends, said guide passages being disposed substantially parallel to each other in a substantially cylindrical arrangement in said pump block, an inlet port and an outlet port opening into each guide passage at axially spaced points therein, a pump plunger slidable back and forth in fluid displacing relation in the end of each guide passage adjacent the inlet port for opening and closing the inlet port and for moving entrapped fluid through the interport passage toward the outlet port, a drive shaft journaled substantially centrally with reference to the cylindrical arrangement of the guide passages in the pump block, power transmission means operatively connecting between said drive shaft and the pump plungers for reciprocating the plungers as the shaft rotates, a check valve plunger slidably disposed in the other end of each guide passage adjacent the outlet port for opening and closing the outlet port, a valve spring for continually biasing each valve plunger into the guide passage to move in past the outlet port and into the interport passage, an engageable projection on each valve plunger, a generally annular stop collar having apertures through which the valve plungers slide for engaging said projection thereon for limiting the movement of each spring pressed valve plunger into each passage, supporting means for adjustably supporting said stop collar for movement to various positions relative to the pump block to predetermine the quantity of entrapped liquid in the interport portion of each passage to be displaced by each inward movement of each pump plunger by adjusting the extent of the insertion of the inner end of each valve piston into the inter-port passage, said supporting means also serving as a hydraulic actuator for moving said stop means, conduit means, and control valve means conductively connected with said hydraulic actuator and said conduit means and arranged for selectively increasing, holding constant, or decreasing the capacity of said pump.

ROSS B. TREER.
